REFRIGERATING APPARATUS

Bertram B. Geyer, Dayton, Ohio, assignor to
General Motors Corporation, Dayton, Ohio, a
corporation of Delaware

Application March 21, 1935, Serial No. 12,243

5 Claims. (Cl. 62—108.5)

This invention relates to refrigeration and particularly to freezing trays used in the freezing compartment of a cooling element of a domestic refrigerator.

5 Flexible non-metallic trays have heretofore been used in domestic refrigerators for freezing water into a plurality of ice blocks or cubes. These trays while being constructed to facilitate the removal of ice cubes therefrom, after the tray 10 has been removed from its support on the cooling element of a refrigerating system, have not been entirely satisfactory. For example, the flexible rubber trays now in use quite frequently become bonded to cooling elements to such a degree that 15 they cannot be removed from the element without damaging or tearing the rubber walls thereof. In other words, during certain conditions within a household refrigerator or after prolonged operation of the refrigerating system associated therewith, a sufficient amount of moisture is condensed on the refrigerating surface of the cooling element, in the form of frost or ice, to cause the tray to become frozen in the cooling element. This frost frequently attains such a thickness as 20 to build up around sides of the tray to such a height that the flexible tray cannot be moved by force applied by hands of the housewife or user. Therefore to remove the tray from the cooling element without damaging same it would be necessary to defrost or melt the ice and frost 25 from the cooling element irrespective of whether such defrosting was desired at that particular time. My invention is directed to an improvement for facilitating removal of a flexible tray 30 from its support on a cooling element or evaporator of a refrigerating system under the conditions explained to avoid the necessity of defrosting the element.

An object of the present invention is to provide 35 an improved tray from which the frozen contents may be easily removed and which tray may be conveniently handled either when filled with water or frozen substance.

Another object of the invention is to provide 40 an improved flexible non-metallic tray having a reinforcing metal frame or support which will not interfere with flexing of the tray to facilitate removal of its frozen contents.

A further object of the invention is to provide 45 a flexible non-metallic tray with a metal frame or support which serves, when force is applied to a portion of the frame as a leverage or camming means for breaking a bond between the tray and its support on the cooling element.

50 A still further object of the present invention

is to provide a flexible non-metallic tray with a two-part metal frame, one part of which frame forms a support for the tray while the other part of the frame forms a combined movable handle and cam means for facilitating removal of the 5 tray from its support on a cooling element.

In carrying out the foregoing objects it is a still further and more specific object of the invention to provide a flexible non-metallic tray with a two-part metal frame for the purpose described in the preceding object which is removable from the tray and is constructed to receive 10 trays of different dimensions.

Further objects and advantages of the present invention will be apparent from the following description, reference being had to the accompanying drawings, wherein a preferred form of the present invention is clearly shown.

In the drawings:

Fig. 1 is a front view of a cooling element of a 20 refrigerating apparatus of the household type showing trays embodying my invention supported by the element;

Fig. 2 is an enlarged vertical sectional view taken on the lines 2—2 of Fig. 1 through the 25 cooling element showing the rack or tray support in elevation with the lowermost tray moved upwardly relative to its support.

Fig. 3 is a vertical sectional view taken on the lines 3—3 of Fig. 2;

Fig. 4 is a side view of a metal frame constructed according to the present invention and adapted to be applied to a flexible ice tray; and

Fig. 5 is a top plan view of the tray frame or support shown in Fig. 4.

Referring to the drawings the reference character 10 designates an evaporator or cooling element adapted to be mounted in the food storage compartment of a household refrigerator cabinet and adapted to be connected to any suitable or conventional refrigerant liquefying and circulating unit (not shown). The evaporator 10 is preferably of the sheet metal variety of the type disclosed in the patent to Ernest Dickey No. 1,972,551 of Sept. 4, 1934 and includes a plurality 40 of refrigerated walls 11 forming a sharp freezing compartment 12. A refrigerated shelf 13 divides compartment 12 of evaporator 10 into a plurality of compartments and forms a flat support for receiving receptacles or trays adapted to contain 45 a substance to be congealed or frozen. The dot-dash lines indicated by the reference character 15 in Fig. 1 represents a coating or layer of frost or ice which, as hereinbefore explained, forms on

walls of the evaporator 10 during certain conditions 50 of the refrigerating system. The tray frame or support 55 of the invention is applied to the outer surface of the evaporator 10 and is supported by the refrigerated shelf 13. The tray frame or support 55 is constructed of a flexible non-metallic material and includes a two-part metal frame 56 which forms a support for the tray 57 while the other part of the frame forms a combined movable handle and cam means for facilitating removal of the tray 57 from its support on the cooling element.

tions within a food storage compartment of a refrigerator cabinet or after prolonged operating of the refrigerating system connected to the evaporator. The reference character 16 designates as a whole a flexible receptacle or tray which is preferably molded in one piece from soft flexible high grade rubber. The tray 16 has partitions 17 therein dividing the interior thereof into two longitudinal rows of separate ice 5 forming compartments or pockets 18. These partitions may be split a considerable distance downwardly from their top edge or they may have small openings interconnecting the pockets 18 to permit equalization of the water level in all the 10 pockets when the tray is filled with water as is conventional and well-known to those skilled in the art. A metal wire loop 19 may, if desired, be set in the molding die when the rubber tray 16 is molded and this wire is thereby molded or im- 15 bedded in the rubber about the upper edge of the tray to facilitate handling thereof. The tray 16 is adapted to be carried by and positioned on the support 13 or on the bottom wall of the evaporator 10 by a two-part metal frame or sup- 20 porting device generally designated by the reference character 20 the construction of which will now be described.

The frame device 20 includes a portion 21 for supporting the tray 16 (see Figs. 4 and 5) and 30 a portion 22 forming a movable part of the device. The portion 21 of frame member 20 includes a pair of longitudinally extending round metal wires 23 adapted to fit in grooves 24 provided in the bottom wall of tray 16 (see Fig. 3) for sup- 35 porting the tray. The pair of wires 23 are secured together by a flat metal member 25 which forms a stationary part of a hinge. The free or rear ends of the pair of wires 23 each has a curved finger member 26 soldered or welded thereto and preferably constructed of spring steel. End portions of wires 23 which are secured to the member 25 each also has a curved finger member 27 similar to the finger 26 secured thereto. Movable portion 22 of the frame device 20 40 comprises a substantially U-shaped steel wire 28 having its portion intermediate the ends thereof formed upwardly and outwardly to provide a handle portion 29 for the device 20. The ends of wire 28 are secured together by soldering 45 or welding same to a flat metal member 31 which member forms a movable portion of a hinge. To complete the hinge a shaft or rod 32 is passed through suitable openings provided in the members 25 and 31 to form the pivot point for the 50 55 metal portions 25 and 31.

In the ordinary use of the device of the present invention tray 16 is set in the frame member 20 and the upper ends of the spring clips or resilient fingers 26 and 27 are then moved or 60 snapped over the top edge of the tray to hold the tray in the frame member 20. The tray 16 is filled with water, or any other substance to be con- 65 gealed or frozen, and is then inserted in the cooling element 10 and positioned upon the freezing 70 shelf 13 or upon the bottom wall of the evaporator by the carrying device 20. It will be noted that when the device is supported on the support of the cooling element the bottom walls of the compartments 18 of tray 16 rest on the flat sup- 75 porting surface due to the rods 23 being received in the grooves 24 of the tray and being flush with the bottom thereof. After the contents of the tray have been frozen the tray ordinarily becomes bonded to its support and if it is desired to re- move the tray 16 from the cooling element the

handle portion 29 of the device 20 may be manually moved downwardly as shown in Fig. 2 of the drawings to break the bond between the tray and its support. This movement of handle 5 29 causes the lower elbow portions of wire 28 to engage the surface of support 13 or the bottom wall of the cooling element 10. Further or additional force applied to the handle 29 causes a rocking movement of the portion 22 of device 20 about the elbow portion thereof engaging 10 the support. This movement causes the portion 21 of device 20 to buckle or pivot about the rod or shaft 32 and to be elevated or tilted and the tray 16 thus moves upwardly relative to its support for causing same to be substantially peeled 15 therefrom. The tray 16 and its carrying or positioning device 20 may then be readily and easily removed from the freezing compartment 12 of the cooling element. It is to be noted that the spacing apart of the rods 23 on device 20 prevents 20 these rods from interfering with the flexing of tray 16 to remove its frozen contents after the device is removed from the cooling element 10 and while the tray is positioned in the device 20. Thus the device of the present invention has all the 25 desired characteristics of a conventional flexible rubber tray while at the same time being provided with means for readily and easily breaking an ice bond between the tray and its support.

The resiliency of the spring fingers or clips 26 30 and 27 renders the device capable of receiving and supporting trays of different dimensions. In other words the spring clips 26 and 27 are capable of being extended inwardly or outwardly and upwardly of the normal position thereof shown in 35 Fig. 4 to secure a tray which is longer and/or higher than the tray 16 shown in the drawings to the device 20. In this manner the device 20 may be employed with a plurality of flexible rubber trays of different size. After the device 20 and 40 the tray 16 therein have been removed from the cooling element as a unit the tray can be removed from the device 20, if desired, for facilitating removal of its frozen contents or for cleaning 45 purposes. However, removal of the tray 16 from the device 20 is not necessary or recommended 50 since the bars 23 are spaced apart to permit sufficient flexing of the tray 16 to remove its contents while same is positioned in the device 20.

From the foregoing it will be seen that I have 55 provided an improved device which facilitates carrying and handling of a flexible non-metallic ice tray. My improved device provides a means for moving the tray relative to its support on a cooling element and thereby insures removal 60 of the tray from the cooling element irrespective of the amount of frost or ice accumulated on the element. My improved device provides a means which substantially peels a flexible nonmetallic tray from its support on a cooling element to thereby prevent tearing of the material from 65 which the tray is molded.

While the form of embodiment of the invention as herein disclosed, constitutes a preferred form, it is to be understood that other forms might 70 be adopted, all coming within the scope of the claims which follow.

What is claimed is as follows:

1. A refrigerating apparatus comprising in combination, a cooling element having a support for receiving an ice tray, a flexible non-metallic freezing tray on said cooling element support, a metal device for carrying and positioning said tray on the cooling element support, said device including a plurality of members se- 75

- cured together and extending longitudinally under said tray for supporting same, a plurality of resilient spring clips secured to said longitudinally extending members and fitting over the 5 top edge of said tray for holding the tray upon the device, and a handle pivotally secured to a portion of said device and adapted when moved about its pivotal mounting to break an ice bond between said tray and its support on the cooling 10 element.
2. In combination with a cooling element of a refrigerating system having a support thereon for receiving and supporting an ice tray, a freezing tray of flexible material on the support of 15 the cooling element, a rigid device for carrying and positioning said flexible tray on the cooling element support, said rigid device having a portion extending under said tray for supporting same, said device including a member secured 20 to said tray supporting portion thereof and engaging a part of the tray to hold the tray upon the supporting portion of the device, said member being disengageable from said part of said tray to permit detachment of the tray from said 25 device, said device also including another portion secured to said tray supporting portion thereof and forming a handle therefor, and said handle portion of said device being movable relative to said tray supporting portion thereof for 30 moving the tray relative to its support on the cooling element.
3. In combination with a cooling element of a refrigerating system having a support thereon for receiving and supporting an ice tray, a flexible 35 non-metallic freezing tray on the support of the cooling element, a metal device for carrying and positioning said tray on the cooling element support, said metal device having a portion extending longitudinally under said tray for supporting same, said metal device including a member secured to said tray supporting portion thereof and engaging a part of the tray to hold the tray upon the supporting portion of the device, said member being disengageable from said 40 tray.
4. In combination with a cooling element of a refrigerating system having a support thereon for receiving and supporting an ice tray, a flexible 15 non-metallic freezing tray on the support of the cooling element, a metal device for carrying and positioning said tray on the cooling element support, said metal device having a portion extending longitudinally under said tray for supporting same, said metal device including a member secured to said tray supporting portion thereof and engaging a part of the tray to hold the tray upon the supporting portion of the device, said member being disengageable from said part of said tray to permit detachment of the tray from said device, and a handle pivotally secured to a portion of said device and adapted when moved about its pivotal mounting to break an ice bond 20 between said tray and its support on the cooling element.
5. In combination with a cooling element of a refrigerating system having a support thereon for receiving and supporting an ice tray, a flexible 25 freezing tray on the support of the cooling element, a rigid device for carrying and positioning said flexible tray on the cooling element support, said rigid device having a portion extending under said tray for supporting same, said device also 30 having a spring member or members secured to at least one end of the tray supporting portion thereof and extending upwardly therefrom, said spring member or members being resiliently fitted over the top edge of the tray to provide a unitary 35 structure, and said member or members being detachable from the top edge of said tray to permit separation of the tray from said device.

BERTRAM B. GEYER.
